TAPE EMBOSsing TOOL

Frank W. Hauser, Santa Monica, Kunio Ace Sumida, Los Angeles, and Stephen G. Hauser, Van Nuys, Calif., assignors to Dashew Business Machines, Inc., Los Angeles, Calif., a corporation of Delaware

Filed Mar. 17, 1965, Ser. No. 84,316

Term of patent 14 years

(Cl. D64—10)

FIG. 1 is a top plan view of a tape embossing tool embodying our invention;

FIG. 2 is a side elevational view thereof;

FIG. 3 is a bottom view thereof;

FIG. 4 is a side view opposite to the side shown in FIG. 2;

FIG. 5 is a back view thereof;

FIG. 6 is a front view thereof.

The essential features of the design reside in the portions shown in solid lines.

We claim:

The ornamental design for a tape embossing tool, as shown and described.
